UNITED STATES PATENT OFFICE.

JESSIE ETHYL WILLIAMS, OF PERRY, OKLAHOMA.

BASKET CART.

Application filed September 1, 1926. Serial No. 133,068.

This invention relates broadly to wheeled carriers or trucks, and has for its object the provision of a novel cart of a basket-like formation equipped with rollers or wheels

5 and so constructed and arranged as to hold a clothes basket whereby the basket may be readily transported from place to place without any undue effort on the part of the operator, the device being particularly well de-

10 signed for use in laundries or other places and by housewives and others when clothes are taken from the place where they are laundered into a yard or other place where they are to be hung for drying purposes, the ready 15 portability of the device making it unnecessary for the operator to actually carry the clothes basket from place to place, or to drag it along the ground, as is necessary under ordinary circumstances.

20 Another object of the invention is to provide a device of this character which in addition to possessing the above mentioned advantages will hold the clothes basket or other container at a higher position than if it 25 rested directly on the ground so that it will be unnecessary for the user or operator to stoop so far in picking up the various articles to be removed from the basket or other container and hung upon the line.

30 A further object is to provide a wheeled carrier of a frame construction equipped with a removable fabric lining to serve as a clothes basket there being also pockets for carrying clothes pins, fine pieces to be handled, etc.

35 An additional object is the provision of a device of this character which is readily capable of being folded into compact form so as to be capable of ready storage in a very little space, as for instance behind a door or the like.

40 Yet another object is the provision of a device of this character which will be simple and inexpensive in manufacture, easy to use, positive in action, efficient and durable in service and a general improvement in the art.

45 With the above and other objects and advantages in view, the invention consists in the details of construction and the arrangement and combination of parts to be herein-after more fully described and claimed, and illustrated in the accompanying drawings, in which:—

50 Figure 1 is a perspective view of the device in set up or in operative position,

Figure 2 is a rear elevation thereof, the set up position being shown by full lines and the folded position being shown by dotted lines.

60 Figure 3 is a perspective view of the removable lining,

Figure 4 is a perspective view of one of the pockets.

Referring more particularly to the drawings, I have shown the device as comprising a collapsible frame structure including a pair of curved rear leg members 10 pivoted in crossed relation as indicated at 11 and provided at one end with suitably journaled wheels or rollers 12. The device further includes front leg members 13 and 14, the former of which is similar to the members 10 and provided with a suitably journaled roller or wheel 15, and the latter of 75 which is of somewhat different construction inasmuch as it is shorter and unprovided with a wheel or roller. The members 13 and 14 are pivoted in crossed relation as indicated at 16 and mounted at the pivot point 80 is a yoke or clevis 17 within which is pivoted, at 18, a suitable operating handle 19 provided for the purpose of drawing the device along the ground or other surface. The members 10 and 13 are connected by 85 suitable longitudinally extending bars 20 while the other member 10 and member 14 are connected by similar bars 21 secured thereto in any desired manner.

90 For holding the device in setup position as indicated in Figure 1, use is made of latch members 22 and 23 pivoted, respectively, upon one member 10 and the member 14 as indicated at 24 and 25 and having their free ends notched as shown at 26 for engagement with headed studs 27 or the like carried by the other member 10 and the member 13. Obviously, when these latch members are in engagement with the studs, the device will be held in the setup position 95 disclosed in Figure 1 so as to be capable of supporting a basket or other receptacle containing clothes or other articles.

100 In the use of the device, it will be seen that when it is carrying a basket or other receptacle the operator may draw it about readily by means of the handle 19, this being a much easier procedure than carrying a loaded clothes basket about from place to place in a yard or other place where clothes are 110 being hung. When use of the device is not desired, it is readily apparent that the latch

members 22 and 23 may be disengaged from the studs 27 so that the entire device may be folded into compact form as indicated by dotted lines in Figure 2 so as to be capable 5 of storage within a closet, behind a door or in any other small space.

Instead of the device being used simply to constitute a transporting means for a basket or other receptacle, it may be provided with the lining or container structure 10 disclosed in Figure 3. Referring to this figure in detail, it will be observed that I have provided a container 28 of canvas or other suitable flexible material, this container being so shaped as to fit within the confines of the frame of the device and provided at its edges with pilots 29 adapted to be engaged upon small hooks 30 which are located on the inner or confronting sides of 15 the longitudinally extending frame members 19. At the ends 31 of the container 28 are hems 32 through which may be inserted rods 33 which are slidably engaged through holes 34 in the upper ends of one pair of arms 25 10, these rods having threaded ends 35 adapted to be screwed into threaded sockets 36 in the ends of the other pair of members 10. Obviously, when the receptacle 28 is fastened in this way, it will constitute an 30 efficient carrier for clothes or any other articles to be transported either in a laundry or in the home. Attention is directed to the fact that the receptacle or container 28 is 35 preferably provided with flaps 36 which may be folded over onto whatever articles are being carried so as to constitute a protection for the same and prevent them from being injured by dust, dirt or the like.

Another feature is the provision of flexible 40 detachable pocket members 37 which may be formed of canvas or the like, and which are provided with flaps 38 capable of being held shut by means of coacting snap fasteners 39. These pocket members 37 may be 45 divided into any desired number of compartments by means of partitions 40 as clearly indicated in Figure 4. These pocket members are also shown as provided with eyelets 41 whereby they may be suspended from 50 small hooks 42 on the outer sides of the longitudinal bars or frame members 19.

Clearly, when the device is used for carrying a basket or the like, the receptacle 28 may be entirely removed, along with the 55 pockets 37. However, when it is not desired to use the basket the lining or receptacle 28 may be sprung in position by engaging the eyelets thereof upon the hooks 30 and the pocket members 37 may also be placed in 60 position so that the device will constitute a carrier by itself without it being necessary to use any other receptacle. Instead of the pockets 37 being used for accommodating or carrying clothes pins, it is clear that hand- 65 kerchiefs or other small and fine pieces of

laundry or the like may be placed therein and be kept safely instead of being mixed with the larger and coarser pieces which would be carried in the receptacle 28.

While I have shown and described the 70 preferred embodiment of the invention, it should be understood that I reserve the right to make such changes in the form, construction and arrangement of parts as will not depart from the spirit of the invention or the 75 scope of the subjoined claims.

Having thus described the invention, I claim:

1. A device of the character described comprising a frame including reversely curved 80 end members connected by longitudinally extending bars and pivoted in crossed relation, the members at one end being equipped with rollers and one member at the other end being equipped with a roller, and a handle 85 pivotally mounted at said second named end.

2. A device of the character described comprising a collapsible frame including a pair 90 of reversely curved end members pivoted in crossed relation and carrying rollers, a second pair of end members of curved formation pivoted in crossed relation, a roller 95 journally carried by one of the second named pair of end members, a clevis mounted at the pivot point of the second named members, a handle pivotally mounted within the clevis, and means for holding the members in setup position.

3. A device of the character described comprising a collapsible frame including a pair 100 of reversely curved end members pivoted in crossed relation and carrying rollers, a second pair of end members of curved formation pivoted in crossed relation, a roller 105 journally carried by one of the second named pair of end members, a clevis mounted at the pivot point of the second named members, a handle pivotally mounted within the clevis, and means for holding the members in setup position, comprising latch members pivotally 110 mounted on certain of said end members and having notched ends, and headed studs carried by others of said end members engageable by the latch members.

4. A device of the character described comprising a frame including reversely curved 115 end members connected by longitudinally extending bars and pivoted in crossed relation, the members at one end being equipped with rollers and one member at the other end being equipped with a roller, and a handle pivotally mounted at said second named end, suspension elements carried by the frame, and a flexible receptacle engaged within the frame and suspended from said suspension 120 elements.

5. A device of the character described comprising a frame including reversely curved 125 end members connected by longitudinally extending bars and pivoted in crossed relation,

the members at the end being equipped with rollers and one member at the other end being equipped with a roller, and a handle pivotally mounted at said second named end, 5 suspension elements carried by the frame, and a flexible receptacle engaged within the frame and suspended from said suspension elements, suspension elements mounted on the outside of the frame, and detachable 10 pocket members of flexible material suspended from last named suspension elements. 6. A device of the character described comprising a frame including reversely curved end members connected by longitudinally extending bars and pivoted in crossed relation, the members at one end being equipped with 15 rollers and one member at the other end being equipped with a roller, and a handle pivotally mounted at said second named end, hooks on the inside of the frame, other hooks 20 on the outside of the frame, a receptacle of flexible material disposable within the frame and having eyelets engageable upon the first named hooks, the ends of said receptacle having hems, rods engageable through the hems and through openings in the frame, and flexible pocket devices located outwardly of the frame and having eyelets engageable upon the second named hooks. 25

In testimony whereof I affix my signature.

MRS. JESSIE ETHYL WILLIAMS
